UNITED STATES PATENT OFFICE.

ERNEST W. GRAEF, OF CALDWELL, NEW JERSEY, ASSIGNOR TO HENRY J. GAISMAN,
OF WOODMERE, NEW YORK.

TEMPERATURE-CONTROLLING APPARATUS.

Application filed May 1, 1919. Serial No. 294,121.

To all whom it may concern:

Be it known that I, ERNEST W. GRAEF, a citizen of the United States, and resident of Caldwell, in the county of Essex and State 5 of New Jersey, have invented certain new and useful Improvements in Temperature-Controlling Apparatus, of which the following is a specification.

My invention relates to means for controlling the temperature of air entering a carbureter for the production of the mixture required for internal combustion engines in accordance with the extent of throttle opening.

15 In carrying out my invention I provide means to admit heated or cold air to the carbureter in conjunction with means co-operative with the carbureter throttle adapted to prevent the admission of cold air and 20 admit heated air only to the carbureter during the first portion of the movement of the throttle relatively to its closed position, and to prevent the admission of heated air and permit the admission of cold air only 25 to the carbureter during the last portion of the movement of the throttle relatively to its fully open position, and to permit the admission to the carbureter of a mixture of heated and cold air when the throttle is in 30 position between such extremes. By means of my improvement I am enabled to deliver heated air to the carbureter for idling and slow running, to deliver temperate air for intermediate running and to deliver cold 35 air to the carbureter for high speed work of the engine, whereby to effect smooth running at all engine speeds, enabling the use of low grade fuel when desired.

40 My invention further comprises novel details of improvement and combinations of parts that will be more fully hereinafter set forth and then pointed out in the claims.

Reference is to be had to the accompanying drawings forming part hereof wherein

45 Figure 1 is a side elevation illustrating my improvements applied in connection with an internal combustion engine;

Fig. 2 is an enlarged section on the line 2—2 in Fig. 1;

50 Fig. 3 is a partly broken perspective view of a part of the mechanism shown in Fig. 1;

Fig. 4 is a vertical section substantially on the line 4—4 in Fig. 1;

Fig. 5 is a detail of part of Fig. 4;

55 Fig. 6 is a detail section, substantially on

the line 6—6 in Fig. 7, illustrating the valve to control the flow to the carbureter;

Fig. 7 is a section substantially on the line 7—7 of Fig. 6; and

Fig. 8 is a detail plan view of a portion 60 of the carbureter with part of my improvements.

Similar numerals of reference indicate corresponding parts in the several views.

At 1 is indicated an internal combustion 65 engine provided with an exhaust manifold 2 and with a mixture intake manifold 3 connected with carbureter 4, which parts may be of any ordinary or suitable construction. At 5 is a casing or so-called stove for heating the air for the carbureter shown applied to the exhaust manifold 2 and which may be held thereon by screws 6 or in any suitable manner. The casing or stove is shown provided with means at 7, such as openings 70 opposing manifold 2, to admit air to the interior of said casing or stove for heating air therein by means of its thermal relation to the hot exhaust manifold. The casing 5 is provided with a port 8 having a valve 80 seat 9 communicating with a housing or chamber 10 to which the pipe 11 is attached, which pipe leads to the air intake of the carbureter indicated at 12, to supply air to the carbureter mixing chamber in a well 85 known manner. Heated air will flow from the casing or stove 5 through port 8 into housing 10 and thence through pipe 11 to the carbureter. The housing or casing 10 is also provided with an inlet port 13 having 90 a valve seat 14 for admitting cold or atmospheric air thereto, whereby such air may flow solely, or commingled with heated air, through pipe 11 to the carbureter. Valve

means are indicated at 15 for controlling the 95 flow of air through the ports 8 and 13 to pipe 11. I have shown the seats 9 and 14 disposed in spaced relation in such a manner that the valve means 15 may close either of said ports, but not both at once, and may 100 permit both of said ports to be opened simultaneously. In the arrangement disclosed the part 15 is shown in the form of a valve having its opposite faces adapted to co-operate respectively with the seats 9 and 14. Said valve is shown carried by a shaft 16 shown journalled at its upper end in a suitable bearing at 17 in housing 10, which shaft is adapted to operate with the throttle 18 of the carbureter.

In the example illustrated I provide means co-operative between the throttle and shaft 16 to permit said throttle to be opened a suitable distance from its closed position 5 while the valve 15 is away from seat 9 and against seat 14 for admitting heated air to the carbureter and to prevent admission of cold air to the carbureter, and to move the valve 15 with the throttle from its last named 10 partially open position during a portion of its movement with respect to its full open position until a desired point of opening has been reached toward its full open position, whereupon the valve 15 will close against 15 seat 9 and prevent admission of heated air to the carbureter but allow full admission only of cold or unheated air thereto. When the throttle is in intermediate positions the valve 15 will be in a position more or less 20 near either the seat 14 or the seat 9 to vary the admission of heated and cold air to the carbureter, so that a mixture of heated and cold air may be made in desired proportion according to throttle opening. The 25 reverse operations occur during reverse direction of movement of the throttle. As a convenient means for carrying out such results, I connect the valve 15 with throttle 18 in a resilient manner, an example of 30 means for such purpose being as follows:—

To shaft 16 is attached a resilient or spring-acting member 20, which may be in the form of a spring wire, shown attached by means of a screw 21 to a collar 22 secured by screw 23 to shaft 16, the lower end of 35 which spring member is operatively connected with throttle arm or handle 19 by engagement with connecting member 24, as shown having a slot 25, receiving member 20, said member 24 being shown provided with depending pins or projections 26 co-operative with the spaced members of arm 19. The pins 26 are shown located in the 40 joints between said spaced members for rotation by the latter. Member 24 is shown provided with a bore 24^a loosely receiving the lower end of shaft 16 whereby the former is guided and may have movement relatively to and independently of the latter. 45 The valve 15 is thus adapted to be actuated with throttle 18, through the medium of the spring-member 20, when valve 15 is off one of the seats 9 or 14, and the throttle may have continued movement toward closed or 50 open position, respectively, when valve 15 is upon such seat. The space between the valve seats 9 and 14 with respect to the corresponding dimensions of valve 15 is such, with regard to the movement of throttle 55 18, that at a suitable point before said throttle is fully closed the valve 15 will bear against seat 14 to shut off cold air and spring-member 20 will bend to permit continued closing movement of the throttle to 60 fully closed position, and said spring-mem-

ber will retain valve 15 against seat 14 by the tension of such member until throttle 18 is opened to relieve said tension. From that point during further opening of the throttle spring-member 20 will cause corresponding 70 movement of valve 15 by rotation of shaft 16, the latter being carried around by member 20 with throttle arm 19 and head 24 until valve 15 bears against seat 9 to shut off heated air during which time port 13 is 75 gradually opened to admit cold outside air to casing 10 and correspondingly heated air is cut off from such casing. When valve 15 closes port 9, as stated, heated air from the casing or stove 5 will be shut off from pipe 80 11 during further opening of throttle 18 thereby admitting only cold air to the carbureter. Reverse operations occur during re- 85 verse movement of the throttle, that is to say, when the throttle is moved from wide open position the spring-member 20 will retain valve 15 against seat 9 for the previously described movement of the throttle, and when such position is reached tension of member 20 will be relieved from valve 15 90 and said member will carry said valve along with the throttle causing gradual opening of port 9 and admit heated air to casing 10 and pipe 11, while said valve gradually moves toward seat 14 to reduce the inflow of 95 cold air to pipe 11 until valve 15 bears against seat 9, where the tension of the spring-member will hold said valve during continued closing of the throttle, thereby admitting only heated air through casing 10 100 and pipe 11 to the carbureter. It thus will be understood that when the throttle is only partly opened heated air only will be admitted to pipe 11, that when the throttle is correspondingly nearly wide open cold air 105 only from the outside will be admitted to pipe 11, and that between such extremes (that is when the valve 15 is off its seats) both heated air and cold air will be simultaneously admitted to casing 10 and pipe 11 110 for the carbureter, in proportion to the distance of valve 15, from seat 9 or seat 14, for tempering the air admitted to the carbureter.

My improvements give the advantage of 115 enabling heated air to be admitted to the carbureter while the engine is idling or running slowly for the production of a mixture having a proper temperature for economical and smooth engine operation 120 with relatively small volume of mixture in the cylinders, and then the temperature of such air will be modified, at what may be termed the middle range of opening of the throttle, whereby increased volume of mixture 125 is admitted to the cylinders and the temperature thereof is modified by reason of the admission of fresh cold air com- mingled with heated air in ratio proportional to the position of the valve 15 with 130

respect to seats 9 and 14, and for a final range of position of the throttle toward and at wide open position cold air only is admitted to the cylinders so that compression-pressure temperature therein will not be unduly increased with large or full volume of mixture in the cylinders. In other words, by means of my improvements I am enabled to cause the air entering the carbureter to have its temperature proportioned to the compression-pressure temperature resulting from the volume of mixture in the cylinders according to work and load conditions, whereby the mixture will not be over heated at high engine speed, thereby to prevent pre-ignition in the cylinders, and whereby at other engine speeds the requisite temperature of the air for the mixture may be obtained to produce smooth and economical engine operation.

One of the advantages of the construction shown respecting the detachable connection between shaft 16 and the throttle is that the carbureter may be disconnected from shaft 16 without disturbing the latter, and shaft 16 with the casing 10, or the latter with casing 5, may be disconnected from the carbureter without disturbing the latter. The construction described enables the application to existing engine and carbureter installations of my invention without disturbing or changing any installed parts, it merely being necessary to apply casing or stove 5 to the exhaust manifold and the coupling member 24 to the carbureter arm 19. Furthermore, the position of shaft 16 within the bore of member 24 enables guiding of the latter with respect to the carbureter handle 19 and independent rotation of the latter respecting shaft 16 as well as the coincident rotation of the two.

While valve 15 is shown in a single piece of material having faces to co-operate with seats 9 and 14, it will be understood that the same may be made in two separate parts attached to shaft 16.

My invention is not limited to the details of construction and arrangement of parts set forth as they may be changed and modified within the scope of the appended claims without departing from the spirit of my invention.

Having thus described my invention, what I claim and desire to secure by Letters Patent is:—

1. The combination of a carbureter having a throttle and means to supply heated air and cold air to the carbureter, with means co-operative with the throttle and with respect to said air-supply means permitting heated air only to be admitted to the carbureter during a certain portion of the throttle movement and permitting commingling of cold air with the heated air

during a farther portion of the throttle movement.

2. The combination of a carbureter having a throttle and means for supplying heated air and cold air to the carbureter, with means co-operative with the throttle and with respect to said air-supply means permitting heated air only to be admitted to the carbureter during a certain portion of the throttle movement adjacent to its closed position and permitting the admission of cold air only to the carbureter during approximately wide open position of the throttle.

3. The combination of a carbureter having a throttle and means to supply heated air and cold air to the carbureter, with valve means to control the admission of heated and cold air to the carbureter, and means co-operative between said valve means and said throttle to cause the admission to the carbureter of heated air only, during a portion of the movement of the throttle and cold air only during another portion of the movement of the throttle and permitting the admission to the carbureter of cold and hot air during a different portion of the movement of the throttle.

4. The combination of a carbureter having a throttle, means to supply heated air and cold air to the carbureter, ports respectively to admit heated and cold air to the carbureter, valve means to control said ports adapted to permit one port only to be open at a time or both ports open simultaneously, and means co-operative with the throttle and said valve means permitting the latter to close one or the other of said ports during a portion of the movement of the throttle and to permit both of said ports to be open during another portion of the movement of the throttle.

5. The combination of a carbureter having a throttle, means to supply heated air and cold air to the carbureter, ports respectively to admit heated and cold air to the carbureter, valve means to control said ports adapted to permit one port only to be open at a time or both ports open simultaneously, and resilient means co-operative with the throttle and said valve means to cause the latter to operate with the throttle during certain portions of its movement and to cause said valve means to close one or the other of said ports during different movements of said throttle to admit heated or cold air only to the carbureter during one or the other of the last named movements of the throttle.

6. The combination of a carbureter having a throttle and means to supply heated air and cold air to the carbureter with valve means to control the admission of heated and cold air to the carbureter, a shaft for operating said valve means, a spring-acting mem-

ber connected with said shaft, and means operatively connecting said spring-acting member with the throttle to cause movement of the shaft with the throttle and to permit independent movement of the throttle when the valve means closes the admission of heated or cold air to the carbureter.

7. The combination of a carbureter having a throttle, means to supply heated air and cold air to the carbureter, ports respectively to admit heated and cold air to the carbureter, valve means to control said ports adapted to permit one port only to be open at a time or both ports open simultaneously, a shaft for operating said valve means, a spring-acting member connected with said shaft, a connecting member co-operative with said shaft and with said spring-acting member, and means to connect said connecting member with the throttle for causing operation of said shaft by the spring member the latter being adapted to permit the throttle to move when the valve means closes one or the other of said ports.

25 8. The combination of a carbureter having a throttle, means to supply heated air and cold air to the carbureter, ports respectively to admit heated and cold air to the carbureter, valve means to control said ports adapted to permit one port only to be open at a time or both ports open simultaneously, a shaft for operating said valve means, a spring-acting member connected with said shaft, a connecting member having a bore loosely receiving said shaft and having means co-operative with said spring member, said connecting member having means to be detachably connected with the throttle whereby the throttle may move said valve means for a distance to cause the latter to co-operate with one or the other of said ports and whereby said spring means will permit independent movement of the throttle when the valve means closes one of said ports.

45 9. The combination of an internal combustion engine having exhaust and inlet manifolds, an air heating casing in thermal relation to said exhaust manifold, a housing having a port communicating with said casing and a port communicating with atmospheric air, valve means in said housing adapted to close one or the other of said ports only at one time, and a carbureter communicating with the engine intake manifold and with said housing, said carbureter having a throttle and means co-operative between said throttle and valve means to per-

mit the latter to open one of said ports at a time.

10. The combination of an internal combustion engine having exhaust and inlet manifolds, an air heating casing in thermal relation to said exhaust manifold, a housing having a port communicating with said casing and a port communicating with atmospheric air, valve means in said housing adapted to close one or the other of said ports only at one time, and a carbureter communicating with the intake manifold, said carbureter having a throttle, and resilient-acting means connecting the throttle with the valve means to permit the throttle to have continued movement after the valve means closes one of said ports.

11. The combination of an internal combustion engine having exhaust and inlet manifolds, an air heating casing in thermal relation to said exhaust manifold, a housing on said casing having a port leading to atmosphere and a port spaced from the first named port communicating with said casing, a valve operative between said ports to close either port without closing the other port, a carbureter communicating with the inlet manifold and with said housing, said carbureter having a throttle, and resilient acting means connecting the throttle with the valve to move the latter with the throttle and permit the throttle to continue to move independently of the valve after the latter has closed one of said ports, said resilient acting means maintaining said valve in the last named position until the throttle has moved reversely to its last named movement to move the valve from said port.

12. The combination of a carbureter having a throttle, a casing to supply heated air for the carbureter, a housing associated with the casing, a port providing communication between the housing and casing, the casing having a port spaced from the first named port, a valve between said ports to close one of said ports only at one time, a conduit connecting the carbureter with said housing, and means cooperating between the throttle and said valve for operating the valve with the throttle, and comprising means to permit the throttle to move independently of the valve when the latter closes one of the said ports.

Signed at New York in the county of New York and State of New York this 30th day of April A. D. 1919.

ERNEST W. GRAEF.
